F. McLAUGHLIN,
FOUNTAIN LATHER BRUSH,
APPLICATION FILED OCT. 12, 1920.

1,375,404.

Patented Apr. 19, 1921.

UNITED STATES PATENT OFFICE.

FRANK McLAUGHLIN, OF TORONTO, ONTARIO, CANADA.

FOUNTAIN LATHER-BRUSH.

1,375,404.

Specification of Letters Patent. Patented Apr. 19, 1921.

Application filed October 12, 1920. Serial No. 416,549.

To all whom it may concern:

Be it known that I, FRANK McLAUGHLIN, of the city of Toronto, in the county of York, in the Province of Ontario, Canada, 5 have invented certain new and useful Improvements in Fountain Lather-Brushes, of which the following is a specification.

My invention relates to improvements in fountain lather brushes, the bristles of 10 which are to be supplied with fluid, semi-fluid or plastic substance and the object of the invention is to devise means for feeding a fluid, semi-fluid or plastic substance from a container forming a reservoir into the 15 bristles of a brush at a point in proximity to the free ends of the bristles, the discharge opening being located normally at the base of the bristles and it consists essentially of the following arrangement and construction 20 of parts as hereinafter more particularly explained.

Figure 1 is a side elevation of a lather brush to which my invention is particularly adapted.

25 Fig. 2 is an enlarged vertical section through Fig. 1.

Fig. 3 is a sectional plan view on line 3—3, Fig. 2.

Fig. 4 is a sectional view on line 4—4, 30 Fig. 2.

Fig. 5 is a detail of the brush base holder.

Fig. 6 is a detail of the brush base.

Fig. 7 is a detail of the center discharge tube.

35 In the drawings like characters of reference indicate the corresponding parts in each figure.

1 indicates the container or reservoir in 40 which the fluid or semi-fluid such as liquid soap or plastic soap is contained when the device is used in connection with a shaving brush. The container 1 has a spiral thread 2 formed in the cylindrical wall thereof for a purpose which will hereinafter appear.

45 The lower end of the container 1 is flared outward at 3 so as to form an annular hollow bead 4, the center of the bottom being raised upward at 5 and provided at its center with a conical protuberance 6 surrounded 50 by a depression 7 forming an annular groove around the protuberance 6. 10 indicates a cap provided with a central circular orifice 11 and a depending flange 12 provided with a thread corresponding to the thread 2 with 55 which it engages. The cap 10 is provided with a neck 13 having an annular constrict-

ed portion 13^x extending around the orifice 11. The lower portion of the tube 14 is hexagonal in cross section and the upper portion cylindrical on the exterior. The 60 tube 14 extends vertically through the orifice 11 and centrally through the container 1 into proximity to the lower end thereof, a slight clearance being left at such lower end between its interior edge and the protuberance 6 and between its lower end and the base of the groove 7. Although I have described the tube 14 as hexagonal, it will of course be understood that any shape 65 might be employed which will impart a direct longitudinal and guided movement to the piston 41 hereinafter described. 15 indicates perforations formed in the wall of the tube 14 in proximity to its lower end. 16 indicates a collar which surrounds the 70 tube 14 intermediately of its length and is located within the neck 13 of the container 1. The collar 16 fits freely around the cylindrical portion of the tube 14 and its outer periphery is cylindrical so as to fit within 75 the neck 13 in which it is secured. The space between the collar 16 and the constricted portion of the neck 13 is filled with suitable packing 17. 18 indicates a collar 80 which is secured to the tube 14 and is located 85 above the collar 16. 19 indicates a compression spring extending between the collar 16 and the collar 18. The tube 14 is provided with an extension sleeve 14^x secured thereto having a closed upper end and openings 21 in proximity to such closed end. 24 indicates a sleeve which surrounds the extension 14^x and is provided with a shoulder 90 bearing against the lower end of such extension 14^x. The sleeve 24 normally forms 95 a closure for the openings 21. The lower end of the sleeve 24 is provided with a brush base receiving cup 26, the wall 27 of which is provided with a threaded portion 28.

It will be noted particularly on referring 100 to Fig. 3 that the exterior of the sleeve 24 is cylindrical. 30 indicates a lather brush provided with a metal base 31 fitting within the cup 26 and provided with a thread 33 engaging the thread 28 of the cup 26. The 105 base 31 is provided with a cylindrical sleeve 32 fitting around the sleeve 24. The brush and brush base can be easily removed by unscrewing such brush base from the threaded portion of the cup 26. 34 indicates a compression spring extending between the collar 18 110 and the opposing face of the cup 26. The

spring 34 normally forces the cup 26 upward carrying the annular shoulder 29 against the lower end of the sleeve extension 14*. 41 indicates a piston located within the container 1, and provided with a central hexagonal orifice fitting the tube 14. The piston 41 is formed by an upper metal plate 42 and a lower metal plate 43. The metal plate 43 is provided with a depending annular flange 44 which also has a thread 45 rolled therein which engages with the thread 2 of the container 1. 46 indicates a packing of leather or other suitable material located between plates 42 and 43, such plates being secured together by rivets 47 extending through the plates and packing.

Having described the principal parts involved in my invention I will briefly describe the operation of the same.

20 The manipulator of the brush when he desires to supply such brush with soap grasps the brush base holder formed by the cup 26 in one hand and the beaded portion 4 of the container in the other hand. He then forces 25 the parts together compressing the spring 34. By this means the brush base together with the sleeve 24 and the cup 26 is slid downward upon the tube 14 and simultaneously the port openings 21 are projected 30 upward longitudinally of the brush bristles to a point in proximity to the free ends of the bristles. The manipulator of the brush while holding the brush holder 26 and collar 18 secured to the tube 14 stationary with one 35 hand, turns the container 1 with the other hand. As the piston 41 is held from movement by reason of the sides of its central hexagonal orifice binding upon the hexagonal tube 14, the reservoir is carried longitudinally by the tread 2 engaging the thread 45 compressing the spring 19. As soon as the reservoir is manually released the spring 19 carries it downward together with the piston 41 which slides freely down the tube 40 14 to a new position in which it again binds on the tube at the next operation of the reservoir. By this means the soap is forced 45 into the interior of the tube 14 through the perforations 15, the lower end of the tube 50 of course being forced against the base of the groove 7 as the compression spring 19 yields. The soap forced longitudinally of the tube 14 passes through the open port openings 21 onto the bristles of the brush.

55 From this description it will be seen that I have devised a very simple means whereby soap in either fluid semi-fluid or plastic form

may be fed into the bristles of a brush in proximity to the free ends of the bristles.

It may be pointed out that it is of great 60 advantage to discharge the soap onto the free ends of the bristles as such bristles are spread apart at their free ends and not packed together as at their base allowing of the free passage of air into and through this 65 portion of the brush so as to combine more readily with the soap to turn it into lather.

What I claim as my invention is:

1. In a brush, a reservoir, a discharge tube leading from the reservoir, means for 70 forcing the reservoir contents through the tube, a brush head longitudinally movable on said tube, whereby the discharge end of the tube may be carried from the brush base to and away from the free ends of the bristles of the brush.

2. In a brush, a discharge tube adapted to be connected to a reservoir, a brush head having an unobstructed orifice extending through the base thereof and in which the discharge end of the tube slidably fits whereby such discharge end passes out of the orifice into the body of the brush toward the free ends of the bristles when the head is slid inward upon the tube.

3. In a brush, a discharge tube adapted to lead from a reservoir, means for feeding the reservoir contents into the tube to be expelled through the discharge end thereof, a brush head mounted upon the tube to move 90 longitudinally whereby the discharge end of the tube may be carried from the brush base to and away from the free ends of the bristles of the brush, means for limiting the outward movement of the brush upon 95 the tube, and resilient means for forcing the brush head against such limiting means.

4. In a brush, a tube, an extension sleeve having a closed upper end secured on the upper end of the tube and provided with 100 peripheral openings, a brush head formed with a sleeve surrounding the extension sleeve of the tube and normally covering the openings and provided with a stop projection normally engaging the inner end of 105 the extension sleeve and bearing against the tube to guide the head sleeve during its longitudinal movement, and a compression spring surrounding the tube and bearing against a suitable abutment at one end carried by the tube and against the brush head at the opposite end.

FRANK McLAUGHLIN.
